UNITED STATES PATENT OFFICE

EDWARD HENRY PETERSON AND WILLIAM H. ODLUM, OF CHICAGO, ILLINOIS, AS
SIGNORS TO DURO METAL PRODUCTS COMPANY, OF CHICAGO, ILLINOIS, A CORPO-
RATION OF ILLINOIS

VALVE GRINDER

Application filed August 29, 1927. Serial No. 216,042.

The present invention relates to devices for grinding or refacing valves, and particularly valves of the poppet type commonly employed in internal combustion engines:

5 One of the objects of our invention is the provision of a valve grinder of the class described which is more simple, durable and economical than the valve grinders of the prior art and which may be constructed more 10 cheaply, comprising a small number of parts and means for adapting the device for use on the valves of a great number of different types of motors.

Another of the objects of our invention is 15 the provision of a simplified valve grinder assembly comprising a cast metal casing having an integral handle, a cover for said casing, a novel and simple chuck rotatably mounted in the same, means for oscillating 20 said chuck, and a crank for actuating said means.

Other objects and advantages of our invention will appear more fully from the following description and from the accompanying 25 drawings in which similar characters of reference indicate similar parts throughout the several views.

Referring to the drawings:

Fig. 1 is an elevational view of our valve 30 grinder with the cover removed to show the internal mechanism;

Fig. 2 is an elevational view of the same on the lines 2—2 of Fig. 1 in partial cross-section;

Fig. 3 is a detail view of one of the bits and valve engaging plate; and

Fig. 4 is a detail view of another valve engaging plate.

Referring to Fig. 1, 10 indicates in its entirety our valve grinding device which comprises a cast metal casing 11, having an integral handle 12, a rotatable shaft 13 for a chuck adapted to support a bit 14 carrying a valve engaging plate 15. The casing 11 encloses and supports a simplified assembly of actuating mechanism which is indicated in its entirety by the numeral 16.

The casing 11 is preferably formed as small as is possible to enclose the actuating mechanism 16, and for this purpose the cas-

ing may be made with a flat wall 17 of substantially pear shape, bounded by an upwardly extending wall 18 forming an upper opening 19 of the same shape. The wall 18 may be appropriately thickened at a plurality of points, such as the points 20, 21 and 22, to provide sufficient material for threaded apertures 23 employed in securing the cover 24 by screw bolts 25. The threaded apertures 23 may be located at any points which will not interfere with the interior actuating mechanism 16.

The cover 24 comprises a flat plate of metal of substantially the same outline as the wall 17 of the casing and adapted to fit upon the opening 19, being secured upon the casing by the screw bolts 25 passing through said cover into the threaded apertures 23. The casing may be formed with an integral handle 12 at its top, and the handle 12 may be of any convenient shape which will enable the operator to grasp the top of the casing and exert a force downward upon the bit 14.

The casing 11 is preferably formed with an outwardly projecting boss 26 extending at right angles to the rear wall 17 and provided with a bore 27 adapted to form a bearing for a shaft 28. The boss 26 also projects slightly into the interior of the casing, as at 29, forming a thrust bearing inside the casing for a crank 30, further to be described. The shaft 28 comprises a substantially cylindrical member adapted to fit the bore 27 and having a reduced outer end 31 which is threaded to receive a threaded collar 32 and a crank 33 having a threaded aperture 34. The reduced end 31 on the shaft 28 forms a shoulder 35 against which the collar 32 may be screwed to fix this collar on the shaft 28 and the crank 33 may act like a lock nut against the collar 32 securely fastening the crank upon the shaft 28.

The crank 33 comprises a strip of sheet metal of appropriate length having the threaded aperture 34 at one end to fit the reduced end 31, and a second threaded aperture 36 at the opposite end adapted to fit the threaded end 37 of a screw bolt for rotatably securing a knob 38 on said crank. The head of the screw bolt 37 may be prevented from

binding against the knob 38 by providing a limited thread on the bolt 37 so that it cannot be threaded in far enough to pinch the knob 38.

- 5 The casing 11 is also formed with a downwardly extending boss 39 extending from the bottom of the casing at substantially right angles to the bearing 27 and provided with an enlarged bore 40 and a counterbore 41. 10 The boss 39 also projects upward into the casing 11 as at 42 forming a thrust bearing within said casing, and the bore 41 is adapted to rotatably receive a shaft 13.

The shaft 13 has a reduced upper end 43 fitting in the counterbore 41 and forming a shoulder 44 adapted to bear against a washer 45 fitting in the enlarged bore 40. The enlarged bore 40 is also provided with a second washer 46, and a plurality of ball bearings 47 are confined between the washers 45 and 46 to provide an anti-friction thrust bearing for the shaft 13. The lower end of the shaft 13 is provided with a slot 48 and is threaded, as at 49, to receive the internally threaded sleeve 50. The slot 48 should preferably extend to such a distance that the split portions of the shaft 13 may be cammed together by the inner frusto-conical surface 51 of the sleeve 50, and the split end of the shaft 13 is provided with a bore 52 adapted to fit the reduced end 53 of a bit 14.

The sleeve 50 comprises a substantially cylindrical member having an outer knurled surface 54 and an internally threaded surface 55, as well as the frusto-conical surface 51 terminating in the bore 56. The extreme end of the shaft 13, as at 57, may be further reduced, removing the threads 49 and tapering the end of the shaft to frusto-conical form to fit within the surface 51. The shaft 13 is also provided with a pin 58 riveted therein and traversing the bore 52 at its upper end.

The bit 14 comprises a substantially cylindrical metal member having a reduced upper end 53 forming a limiting shoulder 59, and the extreme end of the reduced portion 53 may be milled away as at 60 to provide a non-circular end 61 which will just pass the pin 58 and prevent relative rotation between the bit 14 and the shaft 13. The non-circular portion 61 may be tapered so as to come into wedging engagement with the pin 58. It will thus be observed that the reduced end 53 may be inserted through the aperture 56 in the sleeve 50 into the bore 52 until the non-circular end 61 engages the pin 58, after which the sleeve 50 may be threaded on the shaft 31, the frusto-conical surface 51 camming the two split ends of the shaft together to clamp the reduced end 53 of the bit. The simple chuck thus provided may be manufactured at a very low cost and with a minimum of machining operations.

The lower end of the bit 14 is provided 65 with a slot, as at 62, adapted to receive a plu-

rality of plates 15, 63 and 64 of varying sizes which are adapted to provide the connecting means between the bit and the valves of motors of different types. All of the plates 15, 63 and 64 are provided with central apertures 65 adapted to register with a bore 66 passing through the end of the shaft 13 across the slot 62. The plates may be stamped from sheet metal to the various shapes and sizes shown, and the upper flat edge 67 of the plate should engage the base of the slot 62 when the cotter pin 68 passes through the apertures 65 and bore 66 securing these parts together.

Referring to Fig. 1, the plate 15 is substantially rectangular at its upper end, tapering at its lower end 69 somewhat after the manner of a screw-driver, and the lower end is adapted to engage in a slot 70 in the valve 71. The plate 63 is intended to engage with valves of larger size, being of substantially rectangular shape with outwardly extending lugs 72 at one side spaced as far as possible and outwardly extending lugs 73 on the opposite side spaced a lesser distance and adapted to fit a different type of valve. In a similar manner the plate 64 has a pair of lugs 74 on one side spaced a distance greater than that of the lugs 72, while the lugs 75 are spaced still more than the lugs 74, thereby providing a series of valve engaging members which are adapted to fit valves of practically any commercial internal combustion engine. The device is also preferably provided with a supplementary bit 76 of similar form to the bit 14, but considerably shorter, enabling the operator to get at valves where the space is limited.

The upper end of the shaft 13 is reduced, as at 77, providing a shoulder 78 for supporting a pinion 79. The reduced end 77 is preferably flattened on one side, as at 80, and the pinion 79 may comprise a stamped sheet metal member having teeth 81 and a central aperture with a complementary flattened side. The end 82 of the shaft may be further reduced and threaded to receive an internally threaded nut 83 and the pinion 79 is preferably secured by means of said nut with a washer 84.

The wall 17 of the casing may be provided with another boss 85 having a threaded bore 86 and projecting in the casing as at 87 to form a thrust bearing for a segmental gear 88. The segmental gear 88 comprises a stamped sheet metal member having a plurality of teeth 89 which are complementary to the teeth 81 of the pinion and having a bore 90 located at the center of curvature. The segmental gear 88 may be rotatably supported in the casing by a screw bolt 91 having a reduced threaded portion 92 and an annular shoulder 93. The shoulder 93 is adapted to limit the inward threading movement of the bolt 91 so that the gear 88 is rotatably sup-

ported on the bolt without being compressed between the head and the boss 87.

The gear 88 and the crank 30 are both provided with countersunk apertures 94 which are adapted to receive bolts 95 of similar shape to the bolt 91. The bolts 95 pass through a sheet metal link 96 into the countersunk bores 94 on the gear 88 and crank 30, respectively, and when the bolts 95 have been riveted in the counterbores they provide a pivotal connection for these parts which will not bind the link. The crank 30 may also be provided with a countersunk bore 97 which is adapted to receive the reduced end 98 of the shaft 28, the end of the shaft being riveted in said bore to fix the crank on said shaft. The link 96 is slightly curved in order to avoid interference with the casing at 21 and with the screw bolt 91.

20 The assembly of the foregoing parts will be obvious to one skilled in the art, but a convenient method of assembly is to perform the riveting operations which secure the shaft 28, crank 30, link 96 and gear 88 together first, after which these parts may be placed in the casing and secured by the bolt 91. The shaft 13 may then be assembled with its ball bearing in the bore 41 and the pinion 79 secured on the end of the shaft by the nut 83.

30 The operation of our valve grinder is as follows: The grinder is provided with an appropriate bit and valve engaging plate to fit the valves of the internal combustion motor, and an appropriate valve grinding compound may be applied to the valve seat 99.

35 The valve engaging plate 15 may be placed in the slot in the valve and bearing down upon the handle 12, the mechanism may be operated by rotating the crank 33. It is obvious 40 that the crank 30 will impart an oscillating motion to the segmental gear 88 because the distance between the bolt 91 and the rivet 95 on the gear is substantially greater than the length of the crank 30. The segmental gear 45 will engage the pinion 79 and impart an oscillating motion to the shaft 13 and valve 71, rotating the valve back and forth upon its seat and grinding away the irregularities of the valve and seat to produce a good fit.

50 While we are aware that many complicated valve grinding devices of the class described have been made, most of these devices embody so many different parts that they are difficult and expensive to manufacture and assemble, and we have provided a simplified assembly of mechanical elements and structure which will perform the operation efficiently and economically and which may be manufactured at a very small cost.

55 60 While we have illustrated and described a specific embodiment of our invention, many modifications may be made without departing from the spirit of the invention, and we do not wish to be limited to the precise details 65 of the construction set forth, but desire to

avail ourselves of all changes within the scope of the appended claim.

Having thus described our invention, what we claim as new and desire to secure by Letters Patent of the United States is:

In a valve grinder, the combination of an elongated supporting casing having a pair of transverse bores with a valve actuating shaft rotatably mounted in one of said bores and extending in the direction of the longitudinal axis of the casing, a counterbore about said shaft, a pair of washers in said counterbore, ball bearings between said washers in said counterbore, an annular shoulder carried by said shaft for engaging one of said washers, a pinion carried by said shaft in said casing, a sheet metal segmental gear having radial teeth on its periphery rotatably mounted in said casing in vertical position to engage said pinion at right angles thereto, a second shaft 70 rotatably mounted in the other bore of said casing, a crank lever fixedly secured to said second shaft, a crank for actuating said second shaft, pivot posts riveted to said crank lever and to said segmental gear, and a connecting link pivotally secured to said crank lever and said segmental gear by said pivot posts, said crank lever being of less length than the radial distance of the pivot post on said segmental gear from the axis of said 75 segmental gear.

In witness whereof, we hereunto subscribe our names this 26 day of August, 1927.

EDWARD HENRY PETERSON.
WILLIAM H. ODLUM.
